UNITED STATES PATENT OFFICE.

GEORGE FRANCIS ROBERTSON, OF TAYLORSVILLE, KENTUCKY.

STATION-INDICATOR.

SPECIFICATION forming part of Letters Patent No. 279,436, dated June 12, 1883.

Application filed March 17, 1883. (No model.)

To all whom it may concern:

Be it known that I, GEORGE F. ROBERTSON, of Taylorsville, in the county of Spencer and State of Kentucky, have invented a new and useful Improvement in Station and Street Indicators, of which the following is a full, clear, and exact description.

The object of my invention is to provide an apparatus for use on railway-cars for indicating stations, or on street-cars for showing the names of streets as they are passed.

Reference is to be had to the accompanying drawings, forming a part of this specification, in which similar letters of reference indicate corresponding parts in all the figures.

Figure 1 is a sectional elevation of the indicator as arranged for use. Fig. 2 is a front elevation of the ratchet mechanism in larger size. Fig. 3 is a top view of the ratchet mechanism 20 with a portion of the upper roller. Fig. 4 is a front view of the same parts, with the inclosing-case in section. Figs. 5 and 6 represent modifications.

The mechanism is contained in a suitable case, A, that is to be placed in the car in position where it can be plainly seen. In the side of the case is a transverse opening, a, at which the name of the station or street will be displayed, the openings being preferably covered 30 with glass, and the case will be also provided with a door for giving access to the mechanism.

B is an upper, and C is a lower roller contained in case A.

b b are endless belts passing around the rollers, and c c are slats of wood or other material attached to belts b, so as to form an endless belt of hinged flaps, having upon them the names of stations or streets in proper order, which can be brought in succession behind the opening a by the rotation of the rollers.

The operating mechanism is fitted in connection with the upper roller, and consists as follows:

D D are ratchet-wheels fixed side by side a short distance apart upon the axle d of the roller, and with their teeth in reverse of each other. The teeth are preferably in length about the width of slat c.

E is an arm or pawl carrier hung loosely on shaft d, and carrying on a pin, e', two pawls, e, that each engage one of the wheels D. The

pawl-carrier is provided with a balance-weight, f, and serves to retain the carrier in a vertical position, and also return it to that position after being turned to either side. 55

g is a curved brace attached at its ends to case A, and extending between the wheels D beneath pawls e.

h is an arm hung loosely on the pin e', and extending through a slot formed in brace g, 60 where a pin, i, passes through a slot, k, in the arm.

l is a cord or rope connected to the upper end of pawl-carrier E, from which the cord passes in opposite directions through the case A to the 65 ends of the car or other suitable place for operation by the brakeman.

In place of using a rope, the arm E may be fitted for movement by a lever arranged to move the arm in either direction. On street-cars 70 that are turned end for end at the end of the route the lever would be preferable.

In the operation of the apparatus the rope is to be pulled to move the pawl-carrier in one direction as each street or station is reached to 75 the end of the route, and the movement reversed on the return trip. This movement of the pawl-carrier causes the movement of the upper roller by engagement of one pawl with one of the wheels D, and the slats c are thus moved 80 in succession to the opening a. The movement is limited by the length of the slot in arm h, and the pin i, which arrests the movement when the end of the slot is reached. The arm h is formed with shoulders m beneath the pawls e, 85 which act, when the carrier is moved, to raise the pawl not in use and hold it up until the return movement is nearly completed, so that backward movement shall not be given to the roller by that pawl acting on its wheel. The 90 return movement is caused by the balance-weight as soon as the rope is released. It will be seen that the movement is thus automatically regulated and accuracy insured.

In place of using projections m for raising the 95 pawls, the arm h may be formed, as shown in Fig. 6, with holes n, in which pins o are inserted, the pins extending beneath the pawls and raising them sooner or later according to the adjusting of the pins in the holes. When more 100 slats are required they can be carried in a case of convenient length, as arranged in Fig. 1.

The arrangement may be as shown in Fig. 5, and the ratchet mechanism applied to either of the rollers.

This apparatus is inexpensive in construction and durable, as there are no parts liable to get out of order. In place of using rollers for the endless belts, reels may be used having bars corresponding in number to the ratchet-teeth, and formed to receive the slats between them.

Having thus described my invention, I claim as new and desire to secure by Letters Patent—

The combination, with the upper roller of the indicating mechanism and two ratchet-wheels, 15 D D, arranged side by side upon the roller-

shaft d, and having their teeth in reverse directions, of the arm E, hung loosely on said shaft, carrying on pin e' the two pawls e e, and balanced by a weight, f, the curved slotted brace g, carrying pin i, attached to case A, and passing between wheels D under the pawls e, the slotted arm h, having a slot in which the pin i works passing through a slot in brace g, hung loosely on pin e', and the cord l, attached to arm E and passing in opposite directions, as 25 and for the purpose specified.

GEORGE FRANCIS ROBERTSON.
